UNITED STATES PATENT OFFICE.

CARL F. M. ZILL, OF CHICAGO, ILLINOIS.

GAME APPARATUS.

SPECIFICATION forming part of Letters Patent No. 408,869, dated August 13, 1889.

Application filed April 24, 1889. Serial No. 308,406. (No model.)

To all whom it may concern.

Be it known that I, CARL F. M. ZILL, of Chicago, in the county of Cook and State of Illinois, a citizen of the United States, have 5 invented certain new and useful Improvements in Game Apparatus, of which the following is a specification.

The object of my invention is to provide a new and improved game apparatus which is 10 simple in construction and which affords great amusement.

The invention consists in the construction and combination of parts and details, as will be fully described and set forth hereinafter, 15 and finally pointed out in the claims.

In the accompanying drawings, Figure 1 is a plan view of my improved game. Fig. 2 is a vertical longitudinal central sectional view of the same. Fig. 3 is a plan view of a modification. Fig. 4 is a vertical central longitudinal sectional view of the same.

Similar letters of reference indicate corresponding parts.

The circular platform A is provided with 25 an extension B and with suitable supports C, which hold the said platform slightly inclined from the extension B to the diametrically-opposite part. The platform A is surrounded by a raised rim D, and on the inner side of 30 the same a series of pockets or compartments E are formed by partitions E' on that half of the platform opposite the extension B. In the upper surface of the platform a slight depression or cavity F is formed for receiving 35 a ball G at the center of the platform, and at both sides of the same an inclined partition H is provided. A figure J is secured on the top of the platform near the inner end of the extension B, and is provided with an inclined. 40 ball-chute J' and an opening at both ends.

At the upper opening a lip K is provided, upon which the ball M can be placed. A figure O—preferably that of a bird—is pivoted 45 on a hollow casing P, containing a spiral spring R, which presses upward against a disk R', secured on a pin S, projecting downward from the figure O. The ball G is placed in the cavity F and the ball M on the lip K. The tail end of the bird O is then depressed, 50 whereby the spring R is brought in tension,

and when said tail end is released it is thrown upward suddenly by the expanding spring R and its beak strikes the ball M and throws it off the lip K. The ball then slides down the chute J' and runs into one of the pockets E 55 having different numbers. If the ball M strikes the ball G, the latter also rolls into one of the apartments or pockets E, and also counts.

In the construction shown in Figs. 3 and 4 60 the chute J² is arranged vertically and the lip K' projects horizontally. A curved rod Q projects upward from the chute, and from the same the figure T of the bird is suspended, by means of a wire U, and the figure is swung 65 from the front of the upright chute and then released, and its beak passes through the aperture J³ in the front of the chute and strikes the ball M', and throws the same off the lip K'. The ball drops to the bottom of 70 the chute and then rolls over the platform, in the manner previously described.

Having thus described my invention, I claim as new and desire to secure by Letters Patent—

1. In a game, the combination, with a circular platform having a raised rim, and partitions along part of the rim forming compartments, inclined partitions on said platform near the center, a chute on the platform, a lip for receiving a ball on said chute, and a 75 swinging figure adjacent to said lip, whereby when the figure strikes the ball resting on said lip the ball rolls through the chute upon the game-board, substantially as set forth.

2. In a game, the combination, with a platform having a raised rim, of partitions forming compartments along part of said rim on the top of the platform, an upright chute at that part of the platform opposite the compartments, a lip on said chute for holding a 80 ball, and a swinging figure adapted to strike 85 against said ball, substantially as set forth.

In testimony that I claim the foregoing as my invention I have signed my name in presence of two subscribing witnesses.

CARL F. M. ZILL.
